SUBMARINE SIGNALING SYSTEM

Filed May 31, 1922

Inventor:
John J. Gilbert
by C. A. Sprague, Atty.

UNITED STATES PATENT OFFICE.

JOHN J. GILBERT, OF PORT WASHINGTON, NEW YORK, ASSIGNOR TO WESTERN ELECTRIC COMPANY, INCORPORATED, OF NEW YORK, N. Y., A CORPORATION OF NEW YORK.

SUBMARINE SIGNALING SYSTEM.

Application filed May 31, 1922. Serial No. 564,915.

To all whom it may concern:

Be it known that I, JOHN J. GILBERT, a citizen of the United States of America, residing at Port Washington, in the county of 5 Nassau and State of New York, have invented certain new and useful Improvements in Submarine Signaling Systems, of which the following is a full, clear, concise, and exact description.

10 This invention relates to artificial electric lines and to transmission systems, and more particularly submarine cable systems, in which such lines are employed.

An object of the invention is to provide 15 an artificial line containing inductance and capacity for simulating the impedance of a submarine cable or other transmission conductor, and designed so that oscillatory currents impulsively produced therein will be 20 confined to a frequency range which will reduce to a minimum their disturbing effect upon other apparatus.

In the following description of the invention reference is made to the accompanying 25 drawing, in which Fig. 1 is a diagrammatic showing of terminal apparatus of a submarine signaling system according to this invention. Figs. 2, 3 and 4 represent currents set up in this apparatus.

30 Referring to Fig. 1, a submarine cable A terminates in the usual duplex bridge arrangement in which the cable forms one ratio arm, the artificial line AL the second arm and the condensers K, K the remaining 35 arms. The transmitter T is connected between condensers K, K and ground and the receiving circuits RC and the receiving- 40 shaping network N are in circuit across the bridge in conjugate relation to the transmitter.

It is necessary to employ lumped or concentrated impedance elements in the artificial line to simulate the distributed impedance of the cable. Since the cable is inductively loaded, the artificial line contains 45 lumped inductance as well as lumped capacity and resistance, which alone are ordinarily employed in the artificial lines of unloaded cable systems. Each section of this 50 artificial line is seen to comprise the necessary elements of an oscillatory circuit. When the local transmitting key is operated, a relatively large current is impressed upon

the cable and the artificial line. The energy thus impressed upon the artificial line is first 55 stored in the reactive elements, after which a redistribution takes place in the natural periods of the oscillatory circuits. Thus impulsively produced oscillatory currents are set up throughout the artificial line, and 60 since no corresponding currents are produced in the cable there is no balance with respect to these currents, which flow through 65 the shaping-receiving network into the receiving instrument where they mask the received signal, unless some means are provided to prevent this action. An object of this invention is to overcome this disturbance.

Fig. 2 represents the instantaneous current impressed upon the cable and the artificial line by closure of the transmitting key. Fig. 3 represents the resulting current 70 set up in a filter section, which current consists of the vertical front 1 and the oscillatory portion 2. The resultant disturbing current is shown in Fig. 4. The amount of interference with the received signal, due to unbalance thus produced, depends upon 75 the amplitude and the period of the several pulses. The receiving apparatus is usually designed to be highly sensitive to pulses having the same period as those involved in the received signal and to discriminate 80 against pulses having shorter periods. If, 85 for example, the signaling speed corresponds to 60 cycles per second, the range of frequencies involved in signaling is from 60 cycles to two or three times this frequency.

The periods and amplitudes of the disturbing oscillatory currents can be calculated by mathematical formulæ from which it appears that both quantities decrease as 90 the equivalent length of a section of the artificial line is decreased; that is, as each of the sections is made to simulate a shorter section of the cable. A complete exposition of the development of these mathematical formulæ may be found in a paper by John K. Carson entitled "Theory of the transient oscillations of electrical networks and transmission systems," published in the Proceedings of the American Institute of Electrical Engineers, March, 1919. In a particular 100 case, for example, of the cable having ca-

5 capacity of .4 microfarads per nautical mile and an inductance of 60 millihenrys per nautical mile the period of the oscillations was found to be

$$T=3.02\sqrt{CL}$$

10 where C and L are the values of the capacity and inductance in a section of the artificial line. If X is the equivalent length of the section in nautical miles, then 15 $C=4\times 10^{-6}X$, $L=.06X$ and $T=4.58\times 10^{-4}X$. According to this invention the value of X is chosen so that T is less than a prescribed value, which depends upon the degree of discrimination against high frequencies in the receiving apparatus including the receiving network, and upon the speed of operation of the cable.

20 It is not necessary, however, to use such a fine degree of subdivision throughout the artificial line. According to this invention a series arrangement of artificial lines S, S_1 may be used, the equivalent length of each 25 section of the portion S being less than that of each section of the portion S_1 . Other portions may be added having sections of greater equivalent lengths. As shown in Fig. 1 each portion of the artificial line comprises two sections, but the use of a single 30 section or a larger number of sections is within the invention. The sections of portion S are shown as comprising resistance R, inductance L and capacity C, the corresponding elements of portion S_1 having reference characters R_1, T_1 and C_1 respectively. The disturbing oscillation is the resultant 35 of the effects due to the various component artificial lines. The impulsing current from 40 transmitter T is large when impressed upon the first portion S of the artificial line, but is greatly attenuated by the time it reaches portion S_1 so that the amplitude of the disturbing oscillations is relatively small. In 45 addition, the latter disturbances, in order to arrive at the receiver must traverse considerable lengths of the artificial line, and since the attenuation due to the line is very great for the frequencies involved in these 50 disturbances, they will arrive at the receiver greatly reduced in amplitude. It is for these reasons that the equivalent length of each section of the portion S_1 of the artificial line may be of such magnitude that 55 the impulsively produced disturbing currents are within the range of frequencies involved in the reception of the signal. They are so highly attenuated that the disturbing effect is negligible. Their frequency of 60 course may fall within a portion of the range to which the receiving apparatus is not especially sensitive. If desired, the artificial line could be extended to include another portion or portions having sections of 65 equivalent lengths such that the frequency

of the disturbing currents would lie in a portion of the received frequency range to which the receiving instrument is more sensitive.

The invention has been described with 70 special reference to a submarine signaling system but it is obvious it is not so limited in its application. The appended claims cover the invention both broadly and specifically. 75

What is claimed is:

1. The combination at a signaling station of a source of signaling current with a signal receiving means more readily responsive to certain frequencies than to others, 80 and an electrical network upon which current from said source is impressed, said network comprising a plurality of sections each having lumped inductance and capacity of such value that oscillatory currents impulsively produced in said sections by said source of signaling current do not have frequencies to which said signaling means is readily responsive whereby the disturbing effect of said impulsively produced currents 85 upon said signal receiving means is small. 90

2. The combination with a source of signaling current, of a signal receiving device, and an electrical network upon which current from said source is impressed, said network comprising a plurality of sections each having lumped inductance and lumped capacity, the values of said inductance and capacity for one or more sections electrically nearest said signal responsive device being 100 such that the frequency of the oscillatory current impulsively produced therein by said source of signaling current is such that the oscillatory current has a small disturbing effect only upon said signal responsive device, the 105 capacity and inductance of another section or sections more remote from said signal responsive device having such values that the oscillatory currents impulsively produced therein are of a frequency which would 110 cause a considerable disturbing effect upon said signal responsive device except for the remote association therewith. 115

3. The combination with a source of signaling current at a signaling station, of a signal responsive device at said station, a second source of signaling current for transmitting signals through a transmitting medium to said signal responsive device, and an electrical network at said station and upon which current from said first signaling source is impressed, said network comprising a plurality of sections, each containing lumped capacity and lumped inductance, the capacity and inductance of at least one of 120 said sections electrically nearest said signal responsive device being so proportioned that the frequency of the oscillatory currents impulsively produced therein by said first source of signaling current is outside the 125 130

range of frequencies received by said signal responsive device from said second source of signaling current.

4. The combination with an inductively loaded submarine cable, of conjugately related transmitting and receiving apparatus at each terminal, and a balancing network at each terminal to maintain said conjugate relationship, said network comprising a plurality of sections each having lumped inductance and lumped capacity, the capacity and inductance of the section or sections electrically nearest the receiver being proportioned so that the frequency of the oscillatory currents set up impulsively by the adjacent source of transmitted current is outside the range of frequencies involved in the reception of the signal, whereby the disturbing effect of unbalanced current is minimized.

5. The combination with an inductively loaded submarine cable, of conjugately re-

lated transmitting and receiving apparatus at each terminal, and a balancing network at each terminal to maintain said conjugate relationship, said network comprising a plurality of sections each having lumped inductance and lumped capacity, the capacity and inductance of the section or sections electrically nearest the receiver being proportioned so that the frequency of the oscillatory currents set up impulsively by the adjacent sources of transmitting current is outside the range of frequencies involved in the reception of signals, the inductance and capacity of a section or sections of said network more electrically remote from said receiver being so proportioned that the frequency or frequencies of the impulsively produced oscillatory currents are within said range.

In witness whereof, I hereunto subscribe my name this 27th day of May, A. D. 1922.

JOHN J. GILBERT.
